UNITED STATES PATENT OFFICE

170,477

HANDBAG OR SIMILAR ARTICLE

Irving Pichel, New York, N. Y.

Application November 28, 1952, Serial No. 22,472

Term of patent 3½ years

(Cl. D87—3)

To all whom it may concern:

Be it known that I, Irving Pichel, a citizen of the United States of America, residing in New York city, county of New York, and State of New York, have invented a new, original, and ornamental Design for a Handbag or Similar Article, of which the following is a specification, reference being had to the accompanying drawing, forming part thereof.

Fig. 1 is a front perspective view of a handbag or similar article, showing my new design.

Fig. 2 is a side elevational view of the handbag as shown in Fig. 1.

The opposite side of Fig. 1 is substantially the same as shown on the drawing.

I claim:

The ornamental design for a handbag or similar article, substantially as shown and described.

IRVING PICHEL.
